UNITED STATES PATENT OFFICE.

CHARLES S. LOCKE, OF JOLIET, ILLINOIS.

SPRING-HINGE.

SPECIFICATION forming part of Letters Patent No. 688,957, dated December 17, 1901.

Application filed April 15, 1901. Serial No. 55,921. (No model.)

To all whom it may concern:

Be it known that I, CHARLES S. LOCKE, a citizen of the United States, residing at Joliet, in the county of Will and State of Illinois, have invented certain new and useful Improvements in Spring-Hinges, of which the following is a specification.

My invention relates to hinges provided with springs for automatically closing the doors to which they are applied.

The object of my invention is to provide a hinge of this class which shall be simple in construction and operation and may be readily taken apart or assembled, but which is so constructed that the two main members of the hinge may be separated by simply removing the pintle without disturbing the spring or other parts connected therewith, so that the hinge member containing the spring may be secured to a door-frame permanently, while another door containing the other member of the hinge may be removed and another door containing a similar member may be hung without changing the position of the hinge member on the door-frame.

In the accompanying drawings, illustrating my invention, Figure 1 shows a front elevation of my improved hinge. Fig. 2 shows a rear elevation thereof. Fig. 3 shows a vertical section on the line 3-3 of Fig. 2. Fig. 4 is a top plan view of the hinge in the position shown in Fig. 1. Fig. 5 shows a horizontal section of a portion of the hinge.

One leaf A of the hinge has laterally-projecting ears a^2 a^3 , between which a spring-chamber is formed. One end of the spring C is secured to the wall of the spring-chamber by being passed through an aperture c therein, while the other end of the spring is attached to a hub D, that has a flange d' on its upper end resting on the top of the upper ear a^3 of the leaf A. The central portion of the hub extends through an opening in the top ear a^3 , and this hub is held in place and prevented from being detached by the spring C. The other leaf A' of the hinge has a lower ear a^4 , which projects under the lower ear of the first-mentioned leaf, and an upper ear a^5 , which extends over the top of the hub D. The flange d' of the hub is provided with a series of radial slots d to receive a sliding pin E, that passes through a lug a' on the leaf

A'. This pin has a head or handle e on its outer end, and it is also provided with a head e' on its inner end, entering the slots d , as 55 indicated in Fig. 5. The pin may be moved into and out of the slots, but is prevented from being detached from the lug a' . By means of these devices the tension of the spring C may be adjusted. The pivot pin or 60 pintle B extends through the ears of both leaves and through the hub and spring. When the pintle is in position, the two members of the hinge are pivoted together and operate in the usual way. When the pintle 65 7256 is removed, the two members of the hinge may be separated, but the hub and the spring are securely held in place in one member of the hinge even after the pintle is removed. The lower end of the hub D is formed with a 70 projection or boss d^2 , around which the upper coil of the spring extends, while the end of the spring extends through a lug d^3 , projecting laterally from the boss d^2 . By this arrangement the spring and hub are held in proper alignment. The upper coil of the spring fits the boss d^2 snugly, so that there is no wabbling or chance of any disarrangement of the parts. If it is desired to remove the spring and hub from the spring-chamber, it may be done by turning the spring so as to withdraw the end from the aperture c in the casing and then moving the hub and spring through the aperture in the lug a^3 . The hub and spring will still be firmly connected even after they are withdrawn from the spring-chamber; but they may be disconnected by turning the hub on the pivot formed between the upper end of the spring and the lug d^3 and then moving the hub so as to cause the lug d^3 to slide laterally off the end of the spring. The spring, 80 it will be observed, is held securely in place at its lower end against any vertical movement, and the arrangement is such as to draw the hub downward. The member A of the 85 hinge may be permanently fastened to a door-frame, while the member A' may be secured to a storm-door or a screen-door. In view of the fact that the separation of the hinge members does not necessitate the removal of the 90 spring and parts connected therewith two members A' may be used in connection with each member A. One of said members A' 95 may be permanently attached to a storm- 100

door, while the other is permanently attached to a screen-door, and thus the storm-door may be removed and the screen-door substituted very easily without the necessity of shifting 5 the member A' from one door to the other or of changing the position of the member A on the door-frame. Preferably the front of the spring-chamber is closed by a casing A¹⁰, while the rear portion of the chamber is open, 10 as shown in Fig. 3.

I claim as my invention—

1. A hinge, comprising a leaf formed with upper and lower ears having a spring-chamber between them, a flanged hub extending 15 through an opening in the upper ear and having its flange formed with a series of slots or recesses and resting on the top of the upper ear; a coiled spring arranged in the chamber and having its lower end secured to the wall 20 thereof and held against a vertical movement and its upper end secured to the hub and drawing downwardly thereon, thus serving to hold the hub in place; another leaf having a lower ear arranged under the lower ear of the

first-mentioned leaf, and an upper ear arranged over the top of the hub; a removable pintle extending through the ears of the two leaves and through the hub and spring, and a pin carried by the second-mentioned leaf adapted to engage the slots in the hub. 25

2. A hinge, comprising two members pivotally connected by a pintle, and one of which is formed with a spring-chamber; a coiled spring arranged in said chamber, and having its lower end detachably connected with the 30 wall thereof, but held against a vertical movement; a hub carried by the chambered leaf and having a boss which the upper coil of the spring fits snugly and a lug on the boss through which the upper end of the spring 35 extends, and by means of which the hub is pivoted to the spring.

In witness whereof I hereunto subscribe my name this 10th day of April, A. D. 1901.

CHARLES S. LOCKE.
